UNITED STATES PATENT OFFICE

LOUIS J. LOEFFLER, OF STAPLETON, NEW YORK

TELEPHONE HAND SET

Application filed July 11, 1930. Serial No. 467,272.

This invention relates essentially to a telephone hand set of that type in which the handle carries the receiver and transmitter opposite to each other so that it can be conveniently held to the mouth and the message received by one of the ears of a person.

An object of the invention is to provide a method of mounting the electro magnets of the receiving unit in a tubular casing formed at one end of the handle.

Another object of the invention is to provide means whereby the receiving unit can be removed from the casing so that it can be inspected and any defects in the connections readily repaired.

Another object of the invention is to provide a mouth member at the transmitting end of the casing whereby the volume of sound is intensified by striking against an elliptic shaped cavity formed in the mouth member.

Another object of the invention is to provide the handle with a rectangular compartment suitable for mounting the switches thereon controlling the circuit for the receiving and transmitting devices.

The novel features of the invention are more fully described in the following specification and claims and illustrated in the accompanying drawings in which:

Fig. 1 represents a vertical section of a device embodying this invention.

Fig. 2 is a horizontal section along the line 2—2 of Fig. 1.

Fig. 3 is a similar section taken along the line 3—3 of the same.

Fig. 4 is a vertical section along the line 4—4 of Fig. 1.

Fig. 5 is an inverted plan view of the transmitter.

In the drawings is shown a handle 6 preferably made of hard rubber and having contiguous tubular casings 7 and 8 respectively located at each end of the handle. In the handle is located a rectangular compartment 9 closed by a countersunk plate 9' arranged at the bottom of the handle. The plate has movably mounted thereon push buttons 10 and 11 the object of which will be hereinafter described.

The tubular casing 7 is provided with the usual talking or transmitting unit 12 and a diaphragm 13 fixed to the unit. A circular mouth member 14 made of hard rubber with a circular depression 15 eccentric with the periphery of the member is located adjacent the diaphragm. Within the depression sunk below the top is a series of slots 16 communicating with the cavity 17 of the member 14 which is substantially elliptic as indicated in Fig. 1. In this device the sound waves pass through the slots and strike against the elliptic inner surface of the mouth piece thereby scattering the sound molecules in the cavity over a wide area. The depression is located at an angle to the diaphragm so that the full volume of the sound waves passing through the slots strike the diaphragm at an angle and rebound against the elliptic surface giving resonancy. The member 14 is clamped to the casing by a flanged ring 18 having interior threaded portions to engage the exterior threads at the end of the tubular casing. The usual line circuit connections 19 are shown leading to the transmitting and receiving unit as indicated in Fig. 1.

The receiving devices include a circular perforated ear member 20 having a rim 21 whereby it is clamped fast by means of a flanged interior threaded ring 22 screwed onto the exterior threads at the end of the tubular casing. A diaphragm 24 is placed on the rim. In the interior of the casing is arranged a supporting annular member or thimble having outwardly projecting annular base flange 25 and an inwardly extending annular upper flange 26 with a central opening, the flange 25 at the base of the thimble is forced against the end of the casing by the ring 22 thus clamping the thimble member to the casing. A pair of bobbins or electro magnets 26' are located in the central opening of the thimble and each has a coil of wire 27 wound thereon with terminals 28 at times connected to the transmitter. Each bobbin is provided with a soft iron core or pole member 29 having its upper end bent at right angles as indicated in Fig. 1. The pole member is secured to the flange 26 by means of rivet or bolt 30 passed through an eye in

the pole member and the flange. In the space between the flange and the pole member is arranged a segmental bushing or washer 31 to give rigidity to the connecting parts 5. A key 32 connecting both poles fastens the bobbin to the poles or cores.

The means for closing the circuit of the transmitter and receiver is controlled by the 10 said push button 10 arranged in the bottom 10 of the handle. In the compartment 9 is fixed a frame 33 by means of screws 34 which also secure the plate 9' for closing the compartment. Spring contact blades 35 are fixed to a block 36 secured in the frame. The blades 15 are actuated by the push button 10 thereby closing the circuit leading to the transmitting and receiving units. Spring contact blades 37 secured to the block 36 controlled by the button 11 close a circuit 38 connected to a 20 buzzer at a distant station. The wire electrical connections between the contact blades, the transmitter and receiver are of the usual kind.

I claim:

25 1. A telephone hand set comprising a tubular casing, a perforated ear member secured to the bottom of the casing, a diaphragm located on the ear member, a receiving unit arranged in the casing, said unit 30 including a thimble provided with flanged upper and base portion, electro magnets fastened to the upper flange, and a ring member engaging the casing and ear member made to jam the base flange of the thimble 35 against the bottom of the casing.

2. A telephone hand set comprising a tubular casing, having a threaded end, a circular perforated ear member having a rim positioned at the bottom of the casing, a diaphragm located on the rim, a receiving unit 40 arranged in the tubular casing, said unit including a thimble with an outwardly projecting base flange and an inwardly extending top flange, electro magnets secured to the top 45 flange, and an interiorly threaded ring member engaging the threaded end of the casing to jam the base flange of the thimble against the bottom of the casing, said ring having 50 a flange at its lower end to engage the rim of the ear member.

3. A telephone hand set comprising a tubular casing having a threaded end, a circular perforated ear member having a rim positioned at the bottom of the casing, a diaphragm located on the rim, a receiving unit 55 arranged in the tubular casing, said unit including a thimble with outwardly projecting base flange and inwardly extending top flange, electro magnets located above the diaphragm in the casing, pole members secured to the top flange, and an interiorly threaded ring member engaging the threaded end of the casing to jam the base flange of the thimble 60 against the bottom of the casing, said 65

ring having a flange at its lower end to engage the rim of the ear member.

4. A telephone hand set comprising a tubular casing having a threaded end, a circular perforated ear member having a rim positioned at the bottom of the casing, a diaphragm located on the rim, a receiving unit arranged in the tubular casing, said unit including a thimble with outwardly projecting base flange and inwardly extending top 70 flange, electro magnets located above the diaphragm in the casing, pole members riveted to the top flange, a key for fixing the magnets to the pole members, and an interiorly threaded ring member engaging the threaded 75 end of the casing to jam the base flange of the thimble against the bottom of the casing, said ring having a flange at its lower end to engage the rim of the ear member.

5. In a telephone hand set the combination with a handle having a tubular casing at each end with a receiving and transmitting unit respectively arranged therein, a rectangular compartment located in the handle, a plate to close the compartment, a frame secured in the compartment, contact switch blades fastened to the frame, blade connections between the transmitting, receiving and a distant audible unit, and a pair of push buttons mounted on the plate for actuating 95 the blades to close the circuits of the respective units.

In testimony whereof I have hereunto set my hand.
